Application November 16, 1945, Serial No. 629,185

4 Claims. (Cl. 101—46)

1

This invention relates to typing, printing and computing machines and more particularly to an improved imprinting action means therefor, although the teachings and concepts thereof may be employed with equal advantage for other purposes.

It contemplates more especially the provision of a simplified, improved, compact and more durable key structures and action devices for combined typewriting and accounting machines, such as illustrated in my United States Letters Patent No. 2,183,920, issued December 19, 1939.

Instrumentalities for typing, computing and accounting machines are common, but these are intricate, involve many parts, and for practical and commercial reasons are applicable for the most part to elaborate accounting and similar devices wherein compactness, simplicity of parts, effective imprinting and dependable operation over extended periods have not been collectively accomplished. In machines involving plural sheets for recording impressions and computations of mechanical devices, the front and back feed visible carriage are respectively very suitable and usually deemed best from a time and labor saving standpoint, intricacy and maintenance and expense being secondary to the results sought. With the teachings of the present invention improved typing and printing instrumentalities are provided for action on plural independent sheets that are capable of either front or back visible feed response. Computing machines embodying the teachings of the present invention are comparatively inexpensive from a structural and production cost standpoint, since very compact, simple, and dependable actions have been incorporated to make possible the use of minimum and small sturdy parts conducive to producing a comparatively low cost machine.

One object of the present invention is to improve the construction and operation of devices of the character mentioned.

Another object is to provide an improved and simplified imprinting action for typing, printing, and computing instrumentalities and the like.

Still another object is to provide an improved computing section for accounting machines which is more compact, dependable and effective.

A further object is to provide an improved computing machine printing action which in-

2

volves few parts, is highly durable, more compact, and less expensive in construction.

Still a further object is to provide improved key actions in conjunction with a simple hammer action for multiple keys for more compactness, dependability and effectiveness.

A still further object is to provide an improved printing hammer and type guide for combined typing and accounting machines.

Other objects and advantages will appear from the following description of an illustrated embodiment of the present invention.

In the drawings:

Figure 1 is a fragmentary top plan view of a combined typing and accounting machine embodying features of the present invention.

Figure 2 is a fragmentary sectional view in elevation taken substantially along broken line II—II of Figure 1 with parts broken away to clarify the showing.

Figure 3 is an enlarged fragmentary front detail view of the cam actuator shaft for operating the hammer and other instrumentalities viewed from line III—III of Figure 2.

Figure 4 is a fragmentary enlarged sectional view in elevation taken substantially along line IV—IV of Figure 1.

Figure 5 is a fragmentary top plan sectional view taken substantially along line V—V of Figure 2.

Figure 6 is a fragmentary top plan sectional view taken substantially along line VI—VI of Figure 2.

Figure 7 is a fragmentary detail sectional view in elevation of the type bar guide and hammer portion.

Figure 8 is a detail plan view of the combined type bar guide and hammer, parts thereof being shown in sections to clarify the showing.

Figure 9 is a fragmentary sectional view of the computing type bar actuators taken substantially along line IX—IX of Figure 1.

Figure 10 is a fragmentary sectional view in elevation taken substantially along line X—X of Figure 9.

Figure 11 is an enlarged detail side view in elevation of the computing bar follower guide.

Figure 12 is an end view in elevation of the computing bar follower guide shown in Figure 11.

Figure 13 is a sectional view taken substantially along line XIII—XIII of Figure 11.

Figure 14 is a bottom plan view of the computing type bar follower guide shown in Figure 11.

Figure 15 is a fragmentary sectional view taken substantially along line XV—XV of Figure 9.

Figure 16 is an enlarged side fragmentary detail view of the computing bar, guide follower, and actuator assembly shown in Figures 9 and 15.

Figure 17 is a fragmentary front view in elevation of the lower end portion of a computing type bar.

Figure 18 is a side view in elevation of a complete computing type bar.

Figure 19 is a sectional view in elevation taken substantially along line XIX—XIX of Figure 18.

The structure selected for illustration is not intended to serve as a limitation upon the scope or teachings of the invention, but is merely illustrative thereof. There may be considerable variations and adaptations of all or part of the teachings depending upon the dictates of commercial practice. The present embodiment comprises instrumentalities mounted on a carriage frame 10 supported by suitable feet 11—12 to rest on a flat surface such as a table or desk. The carriage frame is provided with upstanding side plates 13 for supporting the instrumentalities which are required to secure, feed, and print plural sheets of paper according to the purpose or purposes for which the mechanism and instrumentalities have been designed, assembled and integrated irrespective of the particular term or terms that may be utilized to identify the machine or mechanism for illustrative purposes.

A platen roller 15, having a rubber or other suitable tubular cover 16 disposed thereover, is fixed to a shaft 17 which is journaled in bearings fixed to the side plates 13—14. One or more sheets of paper may be disposed between the feeding rollers (not shown) and the platen 15—16 in a manner specifically illustrated in my co-pending application Serial No. 580,117, filed February 28, 1945.

The sheets are fed by the platen 15—16 within the path of type bar and computing bar actuators for the desired printing and posting thereon as is customary in known accounting machines. The entries are usually identified with descriptive indicia along with the date for each entry effected with the usual type printing bars or keys simulating a standard typewriter mechanism. The posting operation is effected through numeral bars confined in an improved section for operation by adding and subtracting racks, the latter not being any part of the present invention. The present invention concerns itself with the combined arrangement and improved actuation of the type bar and computing bar and their operating instrumentalities.

The descriptive type bars are collectively construed as a typewriter type bar segment to comprise the usual number and arrangement of type bars 18 simulating the make-up of the usual and customary standard typewriter, and are pivoted as at 19 within the radially slotted arcuate mount 20 supported by the frame 10 in the customary manner. The type bars 18 are impressed in relief with the usual upper and lower case indicia 21—22 formed on substantially rectangular plates 23. The indicia plates 23 are suitably attached to correspondingly sized and shaped projections 24 that are laterally offset from and attached to the free extremities 25 of the type bars 18. The usual felt supports 26 serve as a rest for the type

bar projections 24, these being sustained by a substantially L-shaped arcuate bar 27 fixed to the frame 10 adjacent the forward wall 28 thereof.

The type bars 18 have a downwardly offset ear 28' at their pivoted extremity for attachment of a rod link 30 thereto. The rod link 30 extends to and pivotally connects with the free extremity 31 of the link plate 32 pivoted as at 33 within slots 34 depending from the arcuate bracket 27. The link plate 32 is actuated by a vertical rod link 35 and is pivotally connected therewith as at 36 to the central region thereof for operative connection as at 38 to an actuator key arm 37 by reason of the laterally pivotal connection with the lower extremity of the vertical rod link 35. The key arm 37 corresponds in number with the type bars 18, and the former are pivotally connected at their inward horizontal extremity 39 to a transverse bracket 40 fixed to the frame 10.

The springs 41 are anchored at one extremity 42 to the key arms 37, to extend upwardly for anchored connection to the frame 10 as at 43 in order to normally impart an upward urge to the key arms 37 to maintain them in their extreme 20 clock-wise position (viewed from Figure 2) and thereby sustain the key arms 37 in their normally horizontal initial position. The key arms 37 terminate forwardly in an upwardly offset shank 44 which have circular letter and number 25 indicating indicia confining circular key frames 45 attached thereto to correspond with the indicia 21—22 formed in relief on the supporting plate 23. The type bars 18 are displaceable in a clockwise direction responsive to the downward finger 30 tip displacement of the key indicia frames 45 that transmits the displacement to the key arm 37 which, in turn, actuates the key bar 18 in a clockwise direction for striking with impact at a common ribbon frame and site to imprint paper 40 disposed between the feed rollers (not shown) and the platen 15—16 in a manner similar to the operation of a standard typewriter.

The key bars 18 operating responsive to the depression of the key arms 37 coordinate their 45 imprinting with an adding and subtracting bar segment 46 (Figure 5) consisting, in this instance, of side plate members 47—48 having top and bottom cross members 49—50, respectively, disposed therebetween to maintain the side plates 50 47—48 in fixed space parallel relation. The adding and subtracting bar segment 46 is generically referred to herein as a computing segment. The top cross member 49 is of substantially U-shaped configuration (Figure 5) and is 55 secured in position by means of suitable fasteners such as machine screws 50', in this instance two, which maintain a plurality of vertically disposed slide guide plates 51 in horizontal parallel spaced relation. The vertical plates 51 correspond in 60 number to the adding bars which, in this instance, are ten in number to present a corresponding number of numeral digits as will appear more fully hereinafter. It should be observed that the upper and lower extremities of the slide 65 guide plates 51 are provided with substantially rectangular notches to receive the upper and lower cross members 49—50 which are press fitted therein.

Each vertical slide guide plate 51 is provided 70 with a bar follower guide 52 (Figures 2 and 11) comprising, in this instance, a substantially rectangular frame having inwardly extending vertical side members 53—54 disposed between laterally projecting end members 55—56 to present 75 a vertical slide groove 57 (Figure 14) comple-

mental to each vertical plate 51. This arrangement also provides a horizontal cam follower guide groove 58 (Figure 12) to receive the cam end of an actuator lever of the computing type bar segment 46 to be hereinafter described. One of the side members 53 of each bar follower guide 52 is provided with an ear 59 having an aperture 60 provided transversely therethrough for pivotal connection of the lower extremity 61 of an elongated adding bar shank 62. The pivotal connection is effected through a pin 63 that extends through the lower apertured end 61 of the bar adding shank 62 for establishing pivotal connection with the ear 59.

The adding bar shank 62 comprises, in this instance, part of the ten digit computing type bar segment 46. Each adding bar shank 62 extends upwardly to provide a laterally extending imprinting face 64 whereon numeral indicia 65 from zero to nine (0 to 9) reading downward are cast, engraved, or otherwise formed thereon in relief from the top to the bottom in sequence. The laterally extending face plate 64 presents a substantially T-shaped adding type bar 62 (Figure 19), each of which is pivotally connected to the follower guides 52 (Figure 16) for vertical displacement along the plates 51 serving as a slide guide for the follower guides 52. The adding machine bar shanks 62 are each provided with an angularly offset flat spring 66 anchored as at 67 to the rearward edge of the bar shank 62 for downward projection between the lower bar shank extremity 61 and the adjacent edge 68 of the upper cross member 55 provided on each of the bar follower guide frames 52 (Figure 16). The flat springs 66 normally urge the adding bars 62 in a counter-clockwise direction (viewed from Figure 9) against the forward plate 69 (Figures 2 and 4) to maintain them in true vertical alignment in their initial inoperative position. The forward plate 69 is attached between the side plate 47-48 of the adding type bar segment 46 to vertically align with the upper wall 70 of the arcuate mount 20 of the pivoted type bars 18.

It should be noted that the adding bars 62 are of substantially T-shaped cross-section and contact each other along the adjacent edges of their laterally offset face plates 64. The shanks 62 thereof slide through correspondingly shaped and sized slots 71 provided in a horizontal bar 72 (Figure 5) provided between the side plates 47-48 of the adding key segment 46. The bar follower guides 52 also contact each other along their adjacent edges presented by the opposing surfaces of the laterally projecting end frame members 55-56 thereof to afford a compact segment of free sliding elements that are displaced by improved cam type lever actuators 73 (Figures 2 and 9) which serve to reciprocate the bar follower guides 52 vertically along the guide plates 51. In order to accomplish this without pins or pintles such as is customary for computing key segments, the lever actuators 73 each comprise an arm 74 having an integral circular boss conforming to and complementary of a circular bearing and spacer 75 disposed adjacent thereto to serve as a pivotal mounting and contacting bearing therefor.

To this end, the circular bearing and spacer 75 is in registry with the enlarged boss end of the lever arm 74 which is part of a normally offset shorter arm 76 formed integral therewith. The relation of the actuator lever arms 74-76 present a substantially increased oscillatory dis-

placement of the operating end of the actuator lever arm 74 proportional to the increased length thereof over the shorter arm 76. The circular bearing 75 is axially apertured therethrough as at 77 for journaled support on a shaft 78 (Figures 1 and 2) which is mounted in the frame 10 between the side plates 47-48 of the segment 46. Collars 79-80 (Figure 1) are fixed to the shaft 78 to retain the circular bearing and contacting plate 75 of the actuators 73 in assembled contacting relation, there being an actuator 73 for each of the follower guides 52.

The longer lever arm 74 of the actuator 73 converges to merge in a substantially circular cam 81 having rounded sides 82-83 and a flat end 84. The rounded ends 82-83 of the cam 81 are diametrically opposite each other and possess a diameter slightly smaller than the cam follower guide groove 58 and precision fit therein to enable the relative sliding and rotary movement therewith responsive to the oscillatory displacement of the actuator 73 as will be apparent from the full anad dotted outlines of the actuator 73 (Figure 9).

It should be observed that the actuator lever cams 81 are of no greater thickness than the follower guide 58 so that the adjacent corresponding element confine each other against lateral displacement to provide a compact and durable operating connection between the relatively moving parts and improved operating characteristics. Thus, the usual mounting pins which require space and present, at best, intricate assembly and maintenance problems are totally eliminated. The function of the actuator 73 is to index the position of the adding keys or bars 62 responsive to adding and subtracting racks (not shown) that do not constitute a part of this disclosure.

It should be noted that the free extremity of the shorter actuator arm 76 also converges to terminate in a circular cam 85 which has diametrically opposite circular portions 86-87 and a substantially flat end 88. The flat end 88 is, in this instance, notched as at 89 for operative connection with the calculating mechanism (not shown) to present the operating characteristic of precluding the zeros of the indicia 65 to appear in front of the extreme left digit and thus avoid the printing thereof as a prefix digit. The shorter actuator arm 76 of each actuator 73 provides its cam 85 in the path of a rack bar 90 (Figure 2) that serves to return the actuator 73 and its operatively connected bars 62 to their initial position. Coil springs 91 are anchored as at 92 to each of the actuator arms 76, with their other extremity anchored at 93 to the side plate 48 of the adding key segment 46 to normally urge the actuator 76 in a clock-wise direction (viewed from Figure 2).

After the calculating mechanism has predetermined the position of the adding bars 62 of computing segment 46, it becomes necessary to effectuate the printing of the numerals in line with the printing sight through a ribbon that is common to the type bars 18 and the adding bars 62. To this end, a hammer mechanism 94 is provided for all of the adding bars 62. The hammer mechanism 94 consists, in this instance, of a rod 95 that is disposed between the extremities 96 of mounting arms 97-98 (Figures 4 and 8). The extremities 96 which carry the hammer rod 95, are offset from their supporting arms 97-98 that extend downwardly for pivotal mounting as at 99-100 to the side plates 47-48.

of the adding segment 46 (Figure 6). Suitable fasteners such as machine screws 101 extend through the hammer arm extremities 96 for axial engagement of the hammer rod 95 to rigidly support the latter forwardly of the adding bars 62 in impacting relation therewith when the adding keys or bars 62 are elevated in the path thereof from their initial lowered position, for displacing the keys 62 against the platen 15-16 with an impacting force responsive to instrumentalities to be hereafter described.

The hammer supporting arms 97-98 extend downwardly beyond the pivot mount 99-100 to present reduced extensions 102 that carry a rod 103 therebetween for attachment by axially engaging machine screws 104. An annular groove 105 in the rod 103, receives the looped extremity 106 of a coil spring 107 which is anchored at its other extremity to an eyelet 109 (Figure 2) provided with a threaded shank 109 which extends through the type key mount 40 for engagement by a threaded nut 110. With this arrangement, the tension in the coil spring 107 may be adjusted to normally urge the hammer rod 95 in the clockwise direction (viewed from Figure 4) with the lower edges 111 (Figure 4) of the hammer arms 97 normally in contact with actuating cams 112 (Figures 3 and 4) in edge alignment with the hammer arm edges 111.

The cams 112, in this instance two, are mounted on a cam shaft 113 (Figures 3 and 4) which, in turn, are journaled for rotary support in the frame 10 for operation responsive to an electric motor (not shown). The cams 112 have a low portion 114 and a high point 114' which effectuates the extreme impacting displacements of the hammer rod 95 against any of the adding bars 62 which are set upwardly in the path thereof by the calculating mechanism (not shown). Normally, the adding bars 62 are disposed below the path of the hammer rod 95 which are rockably mounted through its arms 97 on the pintles 99-100. Another set of cams 115 (Figure 3), in this instance two, are mounted on the cam shaft 113 to operate the restoring bars 115' in timed relation with the cams 112.

In order for the hammer rod 95 to serve the dual function as a guide for the type bars 18, the hammer rod 95 is slotted as at 116 in alignment with the printing frame to present upstanding, confronting and forwardly extending flanges 117 which are spaced to provide rearwardly converging surfaces 118 that merge with the slot 116 for the reception of the rearwardly offset type bar extremity 25 serving to cooperate with the guide groove 116 and confronting flanges 117 to insure a proper striking position for the type bars or keys 18. Thus, a single hammer rod 95 serves to impart impact to all of the adding bars 62 and also serves as a guide for all of the type bars 18 to insure the proper indexing of the imprinting operation for both the type bars 18 and the adding bars 62. It will be observed, therefore, that the number of parts has been minimized with the result in saving and space, production expense, and improved facility of operation with greater dependability.

The carriage within which the platen 15-16 is rotatively mounted, is horizontally spaced by means of the usual typewriter carriage spacing mechanism. The carriage is confined for guidance in confronting V-shaped guide blocks 119-120 which have the usual confronting racks 121-122 (Figures 1 and 2) provided thereon to properly space the carriage responsive to the

operation of the typing and computing instrumentalities. While the calculating mechanism has not been shown, a brief description of the functional elements of the illustrated structure makes reference to certain associated standard calculating elements with which those skilled in the art are familiar. This reference renders the instant disclosure understandable to those skilled in the art, and will enable a greater appreciation for the improvements constituting the subject matter of the present invention.

It should be noted that for indexing purposes, the numeral keys comprising part of the standard set of type bars 18 make one-half of their normal downward motion and hit a bar for indexing purposes without imprinting. This effects the punching of the indexing pins to space the stop box one position to operate a full set of pins for any one number of a group. To imprint the numbers without adding or subtracting, it should be observed that the stop box is ordinarily one space laterally of the rack bar. The motor for operating restoring levers will then operate the stop box to set at one column to the right of the indexing finger. With the instrumentalities in their initial position, the hammer operating cams 112 have their low point contacting the hammer operating arms 97. The larger cams 115 which control the restoring bars effect the camming edge extending rearwardly with the restoring bars back as far as they can be displaced. Then the motor bar that is readily accessible from the type keyboard, is manually tripped and lifts the built-in motor clutch release to make electrical contact to initiate a full revolution of the motor clutch shaft. In the first part of this action, the hammer rod 95 is moved forward from the platen 15-16 to allow enough space for the adding type bars 62 to rise. The position of the bars 62 are pre-set by the calculating mechanism to enable the elevation thereof through the influence of the actuator springs 91 to serve as the lifting influence thereon within the limits set by a stop box of standard or any suitable construction.

When the motor has turned the cam shaft 113 one-half revolution, the adding type bars 62 have arrived at their upper limit of movement according to the indexing pins set in the stop box, the latter comprising a part of the calculating mechanism (not shown), the cams 112 operate the hammer to cause the type bars 62 to be impacted against the ribbon at the printing frame sight to effect the printing on the sheet that is disposed against the platen 15-16. Now, then, with the start of the second half of the revolution of the cam shaft 113, the hammer 95 is moved forward, the restoring bars are then in a position to shift the adding wheels in mesh with the racks which are limited to corresponding positions of the type bars. As the cams 115 revolve further, the restoring bars 115' are pushed rearwardly, pulling the rack mechanism to the rear and the type bars are synchronously pulled down to their initial position. After the type bars are restored to their initial low position, the cams 112 permit the hammer to move rearwardly under the influence of the spring 107 to the initial position as a type bar guide. This briefly traces a cycle of operation commensurate with a full revolution of the motor which is automatically rendered inactive at the end of each revolution by its own built-in throw-out clutch.

While I have illustrated and described a preferred embodiment of this invention, it must be

understood that the invention is capable of considerable variation and modification without departing from the spirit of the invention. I, therefore, do not wish to be limited to the precise details of construction set forth, but desire to avail myself of such variations and modifications as come within the scope of the appended claims.

I claim:

1. In a device of the character described, the combination with a frame, of a carriage movably mounted on said frame, a platen on said carriage, a computing type bar segment on said frame, a typewriter type bar segment on said frame, a plurality of computing type bars included in said first named segment, a plurality of typewriter type bars included in said second named segment, means for independently positioning each of said computing and typewriter bars relative to said platen, and a combined hammer and bar guide coextensive with all of said computing and typewriter type bars to respectively effect the printing of computing type bars and the guidance of typewriter type bars toward said platen.

2. In a device of the character described, the combination with a frame, of a carriage movably mounted on said frame, a platen on said carriage, a computing type bar segment on said frame, a typewriter type bar segment on said frame, a plurality of computing type bars included in said first named segment, a plurality of typewriter type bars included in said second named segment, means for independently positioning each of said computing and typewriter bars relative to said platen, a combined hammer and typewriter type bar guide common to all of said computing and typewriter type bars, and means adapted to operate said hammer relative to said computing type bar segment and terminate the operation thereof independent of any translation to said carriage to effect the printing of the positioned computing type bars against said platen, said hammer having means thereon for the guidance of typewriter type bars toward said platen when said hammer is inactive with respect to said computing type bar segment.

3. In a device of the character described, the combination with a frame, of a carriage movably mounted on said frame, a platen on said carriage, a computing type bar segment on said frame, a typewriter type bar segment on said frame, a plurality of typewriter bars pivotally connected to said last named segment for displacement to a common printing point, a plurality of computing type bars, slidable follower guide pivotally associated with said computing type bars, parallel guide plates in said computing type bar segment for slidably receiving computing type bar follower guides, actuating lever cams operatively connected to each of said computing type bar follower guides to linearly displace said computing type bars, said slidable follower guides comprising a frame having oppositely open and normally disposed grooves, one of said grooves serving to slidably mount said parallel guide plates,

the other of said grooves serving to linearly and rotatively receive the lever cams therein to linearly displace said cam follower guide along said parallel guide plates responsive to the oscillation of said lever cams, and a hammer coextensive with all of said computing type bars to impact the latter against said platen, there being a transversely flanged cut-out in said hammer to guide the typewriter type bars to the typing point above said typewriter type bar segment.

4. In a device of the character mentioned, the combination with a frame, of a carriage on said frame, a computing type bar segment, a plurality of differentially positionable computing type bars in said segment, means for vertically positioning said computing type bars in said segment, a printing hammer coextensive with said computing type bar segment to confront all of said computing type bars positioned therein for imprinting movement toward said platen, spring means for normally urging said printing hammer against said platen, a typewriting key bar segment, a plurality of typewriting key bars in said last named segment, means for selectively displacing said typewriting key bars toward said platen to imprint against said platen above said printing hammer, a typewriter key bar guide on said hammer to define the printing position of said typewriter key bars therewith when said printing hammer is in its normally inoperative position, and cam means for retracting said printing means against the urge of said spring means, said cam means having an abrupt tripping portion thereon to impact said printing hammer under the urge of said spring means against the positioned computing key bars in the direction of said platen to effect the printing operation, whereby said hammer serves as a guide for said typewriter key bars and as a hammer for said computing type bars in a selected sequence of operations relative to said platen.
